UNITED STATES PATENT OFFICE

158,415

SHIRT

Anna Spector, Chicago, Ill.

Application May 12, 1949, Serial No. 2,612

Term of patent 14 years

(Cl. D3—25)

To all whom it may concern:

Be it known that I, Anna Spector, a citizen of the United States, residing at Chicago, in the county of Cook and State of Illinois, have invented a new, original, and ornamental Design for a Shirt, of which the following is a specification, reference being had to the accompanying drawing, forming part thereof.

Fig. 1 is a front elevational view of a shirt, showing my new design.

Fig. 2 is a rear elevational view thereof drawn on smaller scale, and

Fig. 3 is a fragmentary front view of the shirt shown in Fig. 1 as it appears with the collar turned up.

I claim:

The ornamental design for a shirt, as shown.
ANNA SPECTOR.
